CLASP

Walter S. Painter, Middlebury, Conn., assignor to
 Waterbury Buckle Company, Waterbury, Conn.,
 a corporation of Connecticut

Application February 18, 1939, Serial No. 257,160

6 Claims. (Cl. 24—258)

This invention relates to clasps and more especially to clasps of a type suitable for use with garment supporters.

One object of the present invention is to provide an improved gripper-frame or housing-construction for clasps in which gripper-means is movably arranged in a frame or housing of unchanging size and form and provided with a lever mounted in a wall thereof for actuating the gripper-means from outside of the housing.

Another object of this invention is to provide an improved interlocking arrangement of the gripper device within the said gripper-frame or housing, the latter of which is constructed of peculiar form for the purpose.

Still another object of this invention is to provide, in a clasp of the character referred to, an improved interacting connection between a gripper-actuating lever and the wall of the frame or housing in which the lever is mounted.

A further object of the invention is to provide an improved form of frame or box-like housing which in large measure adds to the ornamental appearance of the clasp.

With the above and other objects in view, as will appear to those skilled in the art from the present disclosure, this invention includes all features in the present disclosure which are novel over the prior art.

In the drawing, which represents an adaptation of a preferred form of the invention to a garment supporter:

Fig. 1 is a view in front elevation of the clasp when in use;

Fig. 2 is a side elevation of the same;

Fig. 3 is an enlarged vertical medial section of Fig. 1;

Fig. 4 is an enlarged transverse section on the line 4—4 of Fig. 1;

Fig. 5 is a vertical medial section similar to Fig. 3, with the gripper parts shown in release position;

Fig. 6 is an enlarged fragmentary vertical section on the line 6—6 of Fig. 5;

Fig. 7 is an enlarged perspective view of the U-loop gripper-spring detached;

Fig. 8 is an enlarged perspective view of the gripper-frame or box-like housing; and

Fig. 9 is an enlarged perspective view of the gripper-actuating lever detached.

The improved clasp herein chosen for illustrating the present invention comprises, with the gripper device to be hereinafter described, a gripper-frame or -housing of box-like form, generally designated by the reference character 10, and

having a rear frame- or housing-wall, generally designated by the reference character 11, and a front frame- or housing-wall generally designated by the reference character 12. The rear and front frame- or housing-walls 11 and 12 are integrally united at the top by oppositely-arranged side-plates 13 and 14 and by an arcuate upper end wall 15.

The rear frame- or housing-wall 11 comprises a back plate 16 having its inner surface 16a constructed and arranged to provide a spring-seat for the U-loop gripper-spring to be hereinafter referred to. As especially well shown in Fig. 8, the rear frame- or housing-wall 11 is provided below the side-plates 13 and 14 with lateral flanges 17, and at the lower end thereof with a combined spring-retaining and gripper-flange 18, all of which flanges are presented forwardly from the back plate 16.

The front frame- or housing-wall 12 comprises a front plate 19 provided with lateral flanges 20—20, and a longitudinal opening 21 with which the gripper-engaging arm of a gripper-actuating lever to be hereinafter referred to, interfits when the gripper device is in release position. At the lower end of opening 21, the front plate 19 is provided with laterally-spaced trunnion-sockets 22—22 to receive oppositely-presented trunnions on the said gripper-actuating lever, in the manner to be hereinafter described.

Disposed within the frame- or box-like housing 10, as shown especially well in Figs. 3 and 5, is a U-loop gripper-spring, which is generally designated by the reference character 23, the said gripper-spring comprising a rear gripper-spring arm 24 seated on the gripper-seat 16a; a front gripper-spring arm 25 which, in the release position of the gripper device, is in seated engagement with the inner surface of the front plate 19 of the front frame- or housing-wall 12; and an intermediate return-bend 26 which is integrally formed with the said front and rear spring-arms 25 and 24.

The gripper-actuating lever, which is generally designated by the reference character 27, is particularly well shown in Fig. 9 and comprises an operating-arm 28 provided with a finger-grip 29 and a gripper-engaging arm 30 which is connected to the operating-arm 28 by an angular bend 31. The gripper-actuating lever 27 is provided with oppositely-presented trunnions 32—32 which project from the lateral edges of the gripper-engaging arm 30 adjacent the angular bend 31. The said trunnions are thus arranged to be pivotally mounted within the trunnion-sockets 22.

22—22, and as shown especially well in Fig. 5, in the release position of the gripper device, the gripper-engaging arm 30 is constructed and arranged to substantially fill the opening 21 in front of plate 19, with its free end 34 in abutment with the marginal-stop formed by the upper edge 35 of the opening 21, the operating-arm 28 extending outwardly from the said front plate 19 at right angles thereto.

10 As shown especially well in Fig. 3, when the operating-arm 28 is moved into engagement with the front plate 19, the gripper-engaging arm 30 is in slidable engagement at its free end with the front gripper-spring arm 25. During this movement of the gripper-actuating lever, the said lever is constrained against lateral displacement by means of abutment-shoulders 33—33 adjacent the trunnions 32—32, the said abutment-shoulders being in movable engagement with the inner edges of the trunnion-sockets 22—22.

By an inspection of Fig. 5, it will be seen that in the release position of the gripper device, the free end 34 of the gripper-engaging arm 30, due to its endwise abutment with the marginal-edge 25 stop-shoulder 35 at the upper edge of opening 21, prevents the longitudinal displacement of the gripper-engaging arm 30 with a resulting dislodgement of the trunnions 32—32 from their sockets 22—22 by the wedging-engagement of the said trunnions with the front gripper-spring arm 25.

As shown especially well in Figs. 3, 6 and 8, the box-like housing 10 for the gripper is provided with a terminal-compartment 36 which is completely closed except at the bottom by back plate 16, front plate 19, side plates 13 and 14, and the arcuate upper end-wall 15.

Referring more especially to Figs. 5 and 6, it will be seen that in the release position of the gripper device, the rear gripper-spring arm 24 is held against lateral displacement on the spring-seat 16a by the lateral-flanges 17—17 of the rear frame- or housing-wall 11, while the front gripper-spring arm 25 is similarly retained against lateral displacement by the lateral-flanges 20—20 of the front frame- or housing-wall 12. At the same time, the rear gripper-spring arm 24 is constructed and arranged to be substantially in endwise abutment at its lower end with the combined spring-retaining and gripper-flange 18 on the rear frame- or housing-wall 11. Furthermore, the several parts are preferably designed to locate the return-bend 26 of the U-loop gripper-spring 23 in abutment with the inner surface of the arcuate upper end wall 15 of the box-like housing 10, as shown especially well in Fig. 6.

In consequence, as the front gripper-spring arm 25 is moved by the gripper-actuating lever 27 to its gripping position, as shown especially well in Fig. 3, it is securely constrained in its movement by the substantially-rigid engagement of the intermediate return-bend 26 at its opposite edges with the arcuate upper end wall 15 and by the retention of the rear gripper-spring arm 24 in secure engagement with its seat 16a. It will be seen, furthermore, that while the rear gripper-spring arm 24 is confined by the lateral flanges 17 throughout substantially its entire length, the return-bend 26 is engaged at opposite sides and in substantially the medial plane of the clasp by the arcuate upper end wall 15. Under these conditions, the wedging engagement exerted by the gripper-engaging arm 30 of the gripper-actuating lever 27 across the

entire width of the front gripper-spring arm 25 adjacent to the free fabric-gripping end thereof, provides an exceedingly effective gripping pressure upon the fabric or garment.

As shown especially well in Figs. 3, 5 and 6, the clasp is provided with a suspension-loop, generally designated by the reference character 37, and comprising a transverse suspension-bar 38; inclined side-reaches 39 with inturned terminals 40 which pivotally interengage with the side plates 13, 14 of the gripper-frame or box-like housing within socket-openings 41—41 formed therein.

According to the embodied form of the invention shown in the drawing, the suspension-loop 37 is mounted in a loop 42 of fabric such, for example, as the strap of a suspender. It is to be noted, in this connection, that by gripping the loop 42 between the thumb and first finger of the right hand, with the finger pressing against the back housing-wall 11, or by gripping the suspension-loop 37 without the use of the loop 42, an effective grip may be secured upon the clasp while the gripper-actuating lever 27 is being manipulated by the left hand.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A clasp, comprising: a rear wall; a front wall; opposite side walls extending between and integrally uniting the said rear and front walls; said side walls being provided with coaxially-aligned suspension-sockets; an arcuate upper end wall integrally-formed with all of the said walls and forming therewith a compartment which is closed except at the bottom; a suspension-loop having its terminals mounted in the said sockets; and a U-loop gripper-spring mounted between the said front and rear walls and having the return-bend intermediate portion thereof arranged within the said compartment.

2. A clasp, comprising: a gripper-supporting frame having a back plate, a front plate, opposite side plates integrally uniting the rear-end portions of said back and front plates, and an arcuate upper-end wall forming with the said back, front and side plates, a compartment which is closed except at the bottom; and a continuous gripper-spring including a rear gripper-spring arm seated in the back plate, a front gripper-spring arm seated in the front plate, and a return-bend intermediately connecting the said gripper-spring arms and arranged within the said compartment.

3. A clasp, comprising: a box-like housing bifurcated at its lower end to provide a gripper-opening intermediately of the front and rear walls thereof, the front wall of said housing being provided with an opening extending therethrough adjacent its lower end and with laterally-spaced trunnion-sockets at the lower end of said opening; a U-loop gripper-spring having a rear gripper-spring arm seated within the box-like housing at the rear, a front gripper-spring arm seated within the said housing at the front and extending past the opening formed therein, and an intermediate return-bend disposed within and at the top of said housing; a gripper-

actuating lever having an operating-arm provided with a finger-grip at its outer end and a gripper-engaging arm constructed and arranged to substantially fill the said front-wall opening, 5 in the open position of the gripper, and having its free edge in endwise abutment with the upper marginal edge of the said front-wall opening, said gripper-actuating lever being provided with oppositely-presented trunnions mounted in 10 the said trunnion-sockets, the said gripper-actuating lever being of the bent-lever type to effect a rearward displacement of the front gripper-spring arm by the displacement of the operating arm of said lever into flatwise position on 15 the front wall of said housing.

4. In a clasp, the combination with a box-like gripper-housing, comprising: vertically-spaced back and front plates; oppositely-arranged side plates integrally uniting the upper-end portions 20 of said back and front plates; an arcuate upper end wall integrally-formed with the said front, back and side plates of the box-like housing; the said back plate being provided with a longitudinal spring-seat, lateral flanges presented 25 forwardly on opposite sides of said spring-seat, and a combined spring-retaining and gripper-flange at the lower end thereof; the said front plate being provided with a lever-receiving opening adjacent the lower end thereof and with laterally-spaced trunnion-sockets at the lower end 30 of said opening; of a U-loop gripper-spring comprising a rear gripper-spring arm mounted on the said spring-seat in the back plate; a front gripper-spring arm seated in the front plate and 35 arranged to cover the longitudinal opening therein in the release position of said gripper; and an intermediate return-bend integrally formed with the said lower and upper gripper-spring arms; and a bent-arm lever provided with trunnions mounted in said trunnion-sockets, the said 40 gripper-actuating lever comprising an operating-arm and a gripper-engaging arm, the latter of which is constructed and arranged to be retained within the said lever-receiving opening and in 45 endwise abutment with the upper marginal edge

thereof by the said front gripper-spring arm in the open position of the gripper.

5. A suspension-clasp, comprising: a front-plate; a back-plate provided with a gripper-spring retaining-flange at its lower end; opposite side-plates extending between the said front- and back-plates at the upper ends thereof and provided with coaxial suspension-sockets; an arcuate end-wall extending between the said side-plates at the top; a suspension-loop having in-turned terminals pivotally mounted in the said sockets; a U-loop gripper-spring comprising a central return-bend portion in edgewise abutment with and subtending a central portion of the said arcuate end-wall, a rear gripper-spring 10 arm seated on the said back-plate and having its lower end in engagement with the said gripper-spring retaining-flange at the lower end of the said back-plate, and a front gripper-spring 15 arm normally seated on the said front-plate of 20 the gripper-supporting frame; and a gripper-actuating lever mounted in the said front-plate to actuate the said front gripper-spring arm.

6. In a suspension-clasp, the combination with a gripper-supporting frame comprising a front-plate, a back-plate, opposite side-plates extending between said front- and back-plates at the upper end of the said gripper-supporting frame, the said opposite side-plates being provided with coaxial suspension-sockets, and an arcuate end-wall extending between the said side-plates at the top; of a suspension-loop having in-turned terminals pivotally mounted in the said sockets; a U-loop gripper-spring disposed between the said front- and back-plates of the clasp and having 30 the return-bend portion thereof extending about the inturned terminal of the said suspension-loop and in edgewise abutment with the said arcuate end-wall in centrally-disposed position with respect to the said side-plates of the said 35 gripper-supporting frame; and a gripper-actuating lever mounted in the said front-plate and in actuating engagement with one of the gripper-arms of the said U-loop gripper-spring.

WALTER S. PAINTER. 45
